UNITED STATES PATENT OFFICE.

ANDREW G. BRANDT, OF SCRANTON, PENNSYLVANIA.

FASTENER FOR UMBRELLA STRETCHERS AND RIBS.

1,417,491.

Specification of Letters Patent.

Patented May 30, 1922.

Application filed March 2, 1921. Serial No. 448,957.

To all whom it may concern:

Be it known that I, ANDREW G. BRANDT, a citizen of the United States, residing at Scranton, in the county of Lackawanna and

5 State of Pennsylvania, have invented certain new and useful Improvements in Fasteners for Umbrella Stretchers and Ribs; and I do hereby declare the following to be a full, clear, and exact description of the invention, such as will enable others skilled in the art to which it appertains to make and use the same.

This invention relates to umbrella construction and more particularly to removable stretchers for umbrellas.

The object of the invention is to provide a simple, efficient and economical device in construction by means of which umbrella stretchers may be easily applied and removed by hand and without the use of tools.

The invention consists in the novel construction, arrangement and combination of parts as hereinafter more particularly described and claimed.

25 One sheet of drawings accompanies this specification as part thereof in which like reference characters indicate like parts throughout.

Figure 1 is a vertical sectional view of a runner member showing one improved detachable stretcher in section and one in elevation;

30 Fig. 2 is an elevation view of a portion of an umbrella stretcher preliminary to affixing the spring hook member;

35 Fig. 3 is an elevation of a part of an improved stretcher with the spring hook member secured in place.

In this invention a stretcher 4 of the usual

40 U-shaped channel construction is used and cooperating therewith is a spring-wire hook member comprising a shank or body 1 which at one end has an angular terminal 2 and at the other a hook 3. This spring hook member is placed between the sides 5 of the stretcher 4 with the shank 1 resting against the bottom of the channel and the hook 3 extending beyond the end of the stretcher as illustrated in Fig. 2. The sides 5 of the

stretcher 4 are then compressed adjacent 50 the end 2 as illustrated in Fig. 3 securing the spring hook member in position.

In its normal position as illustrated in Fig. 1, the shank 1 abuts the bottom of the stretcher whereby to close the hook, but by 55 pressing stretcher 4 as illustrated in dotted lines in Fig. 1, the shank 1 of the hook member is flexed and raised from the bottom of the channel and the mouth of hook 3 is opened permitting the easy removal of the 60 stretcher from engagement with wire 7 which surrounds the slots in ring 8 on the slide runner 9. The ends of the ribs may be similarly provided with hooks adapted for ready removal from a similar ring pivot located 65 adjacent the top of the umbrella.

Having thus described my invention, I claim:

1. The combination of a member of U-channel cross section and a hook member 70 having a spring shank, said spring shank being fixedly secured within said channel member at the end opposite the hook so that the shank will normally lie adjacent the bottom of the channel and the lip of the hook 75 will coat with the ends of the side walls of the channel member to close the hook.

2. In combination with a stretcher of channel cross section, a hook formed of wire having a spring shank part, the end of the 80 shank opposite the hook bent at an angle to said shank and adapted to be fixedly secured between the sides of said channel stretcher so that the spring shank lies in the bottom of the channel, the hook on the other 85 end of said shank adapted to be normally closed by the end of the side walls of the stretcher.

3. The combination of a stretcher of channel cross section and a hook member having 90 a spring shank secured at the end opposite the hook to lie within the channel of said stretcher and to play therein and having on its outer end a hook normally closed by the end of said stretcher.

95 In testimony whereof I affix my signature.

ANDREW G. BRANDT.
